United States Patent Office

Des. 202,481
Patented Oct. 5, 1965

202,481

TYPEWRITER OR THE LIKE

Alfons Boothby, Wilhelmshaven, Peter Sieber, Frankfurt am Main, and Helmut Riffert, Zetel, Germany, assignors to Olympia Werke A.G., Wilhelmshaven, Germany

Filed Dec. 20, 1963, Ser. No. 77,876

Claims priority, application Germany June 22, 1963

Term of patent 14 years

(Cl. D64—11)

FIG. 1

FIG. 3

FIG. 2

FIG. 4

FIG. 1 is a perspective front view of the typewriter showing the new design;

FIG. 2 is a perspective side view of the typewriter, seen slightly from above;

FIG. 3 is a perspective rear view of the typewriter, seen slightly from above;

FIG. 4 is a perspective view of the typewriter, seen from the left front.

The dominant features of the design reside in the integral one piece structure of the hood and frame member, whereby the upstanding keys and the space bar are fully surrounded.

We claim:

The ornamental design for a typewriter or the like, as shown and described.
